UNITED STATES PATENT OFFICE.

HENRY G. BEHRENS, OF CHICAGO, ILLINOIS, ASSIGNOR TO TONK MANUFACTURING COMPANY, OF CHICAGO, ILLINOIS, A CORPORATION OF ILLINOIS.

CRATE FOR PIANO BENCHES AND THE LIKE.

Application filed May 22, 1922. Serial No. 562,665.

To all whom it may concern:

Be it known that I, HENRY G. BEHRENS, citizen of the United States, residing at Chicago, in the county of Cook and State 5 of Illinois, have invented certain new and useful Improvements in a Crate for Piano Benches and the like; and I do hereby declare the following to be a full, clear, and exact description of the invention, such as 10 will enable others skilled in the art to which it appertains to make and use the same.

My invention relates to boxes, crates or the like as employed for shipping objects which are likely to be damaged by the rough 15 handling of such packages, and in general aims to provide an exceedingly simple crate or box construction both for protecting such objects while in transit and for enabling even inexperienced persons to unpack 20 the objects without damage.

In shipping piano benches, tables or similar articles of furniture having highly polished tops and relatively frail legs, it is quite important that all portions of such 25 an article of furniture should be well protected against the likelihood of damage to the same while in transit, and it is likewise important that it should be easy for even an inexperienced person to unpack such items 30 of furniture without damaging the same. However, the high cost of lumber, together with the high freight and express rates make it undesirable to employ heavy packing boxes for such a purpose, while the inter- 35 posing of a suitable filling (such as excelsior) between the article of furniture and the walls of the container adds to the cost and is likely to leave an imprint on the varnish. Furthermore, unless adequate care 40 is used by the party unpacking the box or crate in which such an article of furniture was shipped, this article may easily be damaged during the unpacking and in the case of a polished article of furniture such 45 damage cannot readily be repaired.

My invention aims to provide an arrangement whereby such an article of furniture to be amply protected against ordinary strains encountered in transit by a quite 50 light box or crate, and one which will make it easy even for an inexperienced person to pack or unpack such an article without the risk of damaging the same.

For this purpose, I am able to provide 55 simple means for supporting the packed

article within a box or crate but entirely out of contact with the walls of the latter, aim to arrange the supporting means so that they will readily interlock with certain wall portions of the box or crate, aim to 60 arrange the parts so that the packed article can readily be removed after bodily detaching one of the walls with which the supporting member is interlocked, and aim to dispose other wall portions so that the packed 65 article can readily be slid out upon the latter when it is to be removed. Furthermore, I aim to provide all of these arrangements in an exceedingly simple construction which can readily be employed by inexperienced 70 persons and which will require relatively little and cheap lumber.

Illustrative of my invention, Fig. 1 is a perspective view of a crate embodying my invention and suitable for packing a piano 75 bench.

Fig. 2 is a central and vertical longitudinal section through the same crate with a piano bench supported in it by a single carrier member.

Fig. 3 is a fragmentary horizontal section taken upwardly through Fig. 2 along the line 3—3 of that figure.

Fig. 4 is a vertical section through another form of crate embodying my invention, 85 showing the same as employing two carrier members for holding a table in a substantially floating position.

Fig. 5 is a perspective view of the single carrier member used in connection with the 90 crate in Fig. 1 for supporting a piano bench after the manner of Fig. 2.

Fig. 6 is a perspective view of one of the two carrier members employed for supporting the table in Fig. 4.

Fig. 7 is an elevation of one of the ends of the crate of Fig. 1 as it appears when bodily detached from the crate.

Fig. 8 is a vertical section through a crate embodying my invention and arranged for 100 packing two benches with the upper one inverted.

In packing a piano bench after the manner of Figs. 1 to 3 inclusive, I provide a crate having interior dimensions somewhat 105 greater than the corresponding dimensions of the bench, so that the crate will be adapted to freely house the bench. This crate desirably has a top 1 formed of a substantially single board so as to entirely close 110

the top wall of the crate which is adjacent to the polished top 2 of the bench. It also desirably has side portions 3 and end portions 4 extending downwardly from the top of the crate alongside the sides and ends of the bench. These wall portions are all fastened to suitable uprights 5 which desirably are interbraced by bracing strips 6 and 7 disposed in any suitable manner, as 10 shown for example in Fig. 1.

Instead of providing a closed bottom for the crate, I merely provide a pair of bottom strips 8 each of which extends longitudinally of the crate under one pair of the legs 15 9 of the bench. However, these legs do not rest upon the bottom strips 8 when the bench is packed. Instead, I support the bench substantially in a floating position, entirely out of direct contact with all wall 20 portions of the crate. For this purpose, I employ a carrier member 10 having suitably located perforations 11 for receiving screws which extend upwardly into the ends 12 of the piano bench and which fasten the 25 carrier member securely to the bottom of the bench proper. The main portion of the carrier member is made of a length closely corresponding to the distance between the upper end panels 4 of the crate, and each 30 end of the carrier has an extension 13 projecting beyond this main portion into a corresponding opening in the adjacent end panel of the crate, both the said projection and the said opening being of less width 35 than the main portion 10 of the carrier member. For this purpose, I desirably form each end panel 4 of two abutting portions one of which has a recess 14 opening towards the other portion after the manner of 40 Fig. 1, so that this recess in one of the panel portions will cooperate with the opposed wall of the companion panel portion in affording the desired perforation in the panel.

Thus arranged, it will be evident from the 45 drawings that the carrier member has ends which are practically tenoned to fit into the perforations in the respective end panels of the crate, and by disposing these perforations at a greater distance from the bottom strips 8 of the crate than the height of the legs up to the bottom of the carrier member 10, I cause the bench to be supported with its legs out of contact with the bottom of the crate. By making the interior 50 length of the crate and the corresponding length of the main portion of the carrier member greater than the extreme length of the bench, I can readily cause the bench to be held entirely out of contact with the 55 end walls of the crate, so that my exceedingly simple arrangement enables me to support the bench entirely out of contact with the walls of the crate. Moreover, by providing ample space between the top 2 of the 60 bench and the top 1 of the crate, I can

readily prevent this crate top from being forced down against the top of the bench even if subjected to blows which would tend to dent or warp the top of the crate. Consequently, I do not require excelsior or other 70 packing material to be interposed between the top of the bench and that of the crate.

So also, by keeping the legs out of contact with the bottom of the crate, I prevent strains on this bottom from damaging the 75 usually somewhat frail legs of the bench. In practice, the spacing required for this purpose can be rather small, so that when one end of the crate is detached, the legs adjacent to that end will drop upon the 80 bottom strips 8 without an appreciable jar, after which the bench can readily be drawn out through the opened end of the crate as only its feet will be in contact with the walls of the crate. To facilitate such an easy unpacking, I desirably arrange the crate ends so that each is a unit which can readily be detached from the adjacent walls of the 85 crate. By using crossed braces 7 of thin wood, this can readily be accomplished in 90 a quite light and cheap crate end construction after the manner of Fig. 7.

However, while I have heretofore illustrated and described my invention as embodied in a crate designed for packing a 95 relatively narrow article (such as a bench) and employing only a single carrier member, I do not wish to be limited to this use of my invention, nor to the crate construction thus disclosed. Obviously, the details of 100 construction and arrangement might be varied in many ways without departing either from the spirit of my invention or from the appended claims. For example, Fig. 4 shows a crate used for packing a 105 table and having two carrier members 16 fastened to the bottom of the table, each carrier member having cylindrical end portions fitted into corresponding holes bored in the end walls of the crate. 110

Neither do I wish to be limited to the employment of my invention in a crate or box housing only a single article. For example, Fig. 8 shows a section through a crate as used according to my invention for shipping two piano benches, with the upper one inverted, thereby reducing the shipping space, the packing cost and the freight over that which would be required if each bench 115 were packed separately. 120

I claim as my invention:

1. Means for packing a piano bench or other article of furniture, comprising a crate or box freely housing the said article and having perforations in two opposed walls, 125 and a carrier member detachably fastened to the said article, the carrier member having end portions respectively socketed in the said perforations and having other portions respectively engaging the inner faces of the 130

- 5 said walls; the perforations being so located that when the carrier member has its ends socketed therein the article fastened to the said member is supported by the latter out of contact with the walls of the box or crate.
- 10 2. Means for packing a piano bench or other article of furniture, comprising a crate or box freely housing the said article and having perforations in two opposed walls, and a carrier member detachably fastened to the said article, the carrier member having end portions respectively socketed in the said perforations and having shoulders respectively engaging the inner faces of the
- 15 15 said walls, the perforations being so located that when the carrier member has its ends socketed therein the article fastened to the said member is supported by the latter out of contact with the walls of the box or crate.
- 20 20 3. Means for packing a piano bench or other article of furniture, comprising a crate or box freely housing the said article and having perforations in two opposed walls, and a carrier member detachably fastened to the said article, the carrier member having end portions respectively socketed in the said perforations and having other portions respectively engaging the inner faces of the said walls, the perforations being so
- 25 30 located that when the carrier member has its ends socketed therein the article fastened to the said member is supported by the latter out of contact with both the bottom and the top of the box or crate, the box or crate having bottom portions extending parallel to the carrier member and upon which the article is adapted to be slid out of the box or crate after detaching one of the said opposed walls thereof.
- 35 40 4. Means for packing a table or bench,

comprising a carrier member detachably fastened to the under side of the top of the table or bench and projecting at both of its ends beyond the said top and having a straight tenon at each end, and a box or 45 crate freely housing the table or bench and having each of two opposed walls equipped with a perforation slidably entered by one of the said tenons; the said perforations being further from the bottom wall of the box or crate than the height of the table or bench to the carrier member, so that the table or bench is supported out of contact with the said bottom wall.

5. Packing means as per claim 4, in which 55 each of the said two opposed walls includes a pair of superposed boards one of which has a recess adjacent to the other, the said recess cooperating with the opposed edge of the adjacent board to afford the perforation for receiving the tenon.

6. Means for packing a table or bench, comprising a box or crate of larger interior dimensions than the exterior dimensions of the table or bench, the box or crate having 65 aligned perforations in two opposed walls, and a carrier member detachably secured to the table or bench and having shoulders respectively engaging the opposed faces of the said walls, the carrier member also having extension portions projecting beyond the shoulders and respectively socketed in the said perforations, the perforations in each of the said walls being spaced further from the walls transversely of the latter than the 70 corresponding spacing between the extension portions and the last named walls.

Signed at Chicago, Illinois, May 17th, 1922.

HENRY G. BEHRENS.
